N,N'-SUBSTITUTED DIURETHANES

Norman Rabjohn, Columbia, Mo., assignor to
Curators of the University of Missouri, Columbia,
Mo., a public corporation of the State of
Missouri

No Drawing. Application August 20, 1951,
Serial No. 242,793

8 Claims. (Cl. 260—472)

1

This invention relates to novel chemical compounds and to methods of preparing the same, and, more particularly, it relates to N,N'-substituted diurethanes possessing properties making them especially valuable as pharmaceutical agents.

Procaine, also known as novocaine, (2-diethylaminoethyl p-aminobenzoate) and modified or substituted procaines have proven to be very valuable pharmaceutical agents and have been used widely as anesthetics. However, as is well known, such compounds, as well as other well-known anesthetics, possess certain undesirable properties, especially when administered to sensitive individuals. For example, they produce vasodilatation and stimulate the nervous system, resulting in hyperirritability, restlessness, tremors, and, in lethal doses, eventual death by convulsions. Such undesirable properties are particularly marked in cases of massive infiltration and in the relatively new use of the compounds intravenously.

One object of the present invention is to provide new chemical compounds of advantageous properties.

A further object of the invention is to provide pharmaceutical agents of high anesthetic potency but which, when administered, especially when injected intraperitoneally, will not produce vasodilatation or excitation.

Still another object of the invention is to provide novel anesthetic compounds, which, while possessing the advantageous properties of procaine and similar compounds, will be free from their undesirable characteristics, for example, will lack the undesirable central nervous stimulation properties which are common to procaine and other well-known anesthetics.

Still another object of the invention is to provide an economical method by which the novel compounds of the invention may be prepared.

Other objects will be apparent from a consideration of this specification and the claims.

As stated, the compounds of the present invention are N,N'-substituted diurethanes and, therefore, contain the characteristic diurethan structure:

More specifically, the compounds of the present invention have the following fundamental structural formula:

where X is selected from the group consisting of a saturated straight hydrocarbon chain containing from two to ten carbon atoms; a saturated branched hydrocarbon chain containing from 3 to 10 carbon atoms, an unsaturated hydrocarbon chain containing from four to ten carbon atoms, a phenylene group, a cyclohexylene group, and an ether linkage $-\text{R}'-\text{O}-\text{R}'-$ where R' is selected from the group consisting of ethylene, trimethylene, and propylene; where R is selected from the group consisting of hydrogen or an alkyl group containing from one to four carbon atoms; where R₁ is selected from the group consisting of hydrogen, an alkyl group containing from one to four carbon atoms and an alkoxy group containing from one to four carbon atoms; where R₂ is selected from the group consisting of hydrogen and an alkyl group containing from one to three carbon atoms; where R₃ is an alkyl group containing from one to four carbon atoms; and where R₄ is an alkyl group containing from one to four carbon atoms.

Referring further to X, when X is a saturated or unsaturated hydrocarbon chain, the group may be straight or branched chain. Typical examples of saturated straight hydrocarbon chains which may be present are ethylene, $-(\text{CH}_2)_2-$; trimethylene, $-(\text{CH}_2)_3-$; tetramethylene,

pentamethylene, $-(\text{CH}_2)_5-$; hexamethylene, $-(\text{CH}_2)_6-$; and decamethylene, $-(\text{CH}_2)_{10}-$. Typical examples of saturated, branched hydrocarbon chains which may be present are: propylene, $-\text{CH}(\text{CH}_3)\text{CH}_2-$; 2-methyl trimethylene,

1-methyl trimethylene, $-\text{CH}(\text{CH}_3)\text{CH}_2\text{CH}_2-$; and 3,3, dimethyl pentamethylene,

When X is an unsaturated hydrocarbon chain, it may contain a double bond or a triple bond, typical examples being: 2-butylene,

and 2-butynylene, $-\text{CH}_2\text{C}\equiv\text{CCH}_2-$; 3-hexenylene, $-(\text{CH}_2)_2\text{CH}=\text{CH}(\text{CH}_2)_2-$; 2-hexynylene, $-\text{CH}_2-\text{C}\equiv\text{C}-(\text{CH}_2)_3-$; 5-decenylene,

and 2-decynylene $-\text{CH}_2\text{C}\equiv\text{C}(\text{CH}_2)_7-$. When X is an ether linkage, a straight or branched hydrocarbon chain may be present, typical examples of these ether linkages being bis 2,2' oxydiethyl, $-(\text{CH}_2)_2-\text{O}-(\text{CH}_2)_2-$; and bis 2,2' oxydi-1-methyl ethyl,

Referring to R, R₁, R₂, R₃, and R₄, when these groups are alkyl groups, the hydrocarbon chain may be straight or branched, examples being methyl, ethyl, n-propyl, isopropyl, and, in the case of R, R₁, R₂, and R₄, n-butyl, iso-butyl, and sec-butyl, and where R₁ is an alkoxy group, the corresponding alkoxy groups may be present.

When X is a phenylene group, the linkage of the

groups therewith may be ortho, meta, or para, preferably para. Likewise, when X is a cyclohexylene group, the linkage of the

groups therewith may be 1,2; 1,3 or 1,4, preferably 1,4. In the foregoing structural formula, the

linkage may be located, with respect to the phenylene group there shown, at a position ortho, meta, or para to the carboxyl group, preferably at the para position, and the R₁ group may be located at the ortho, meta, or para position, preferably at the ortho position.

The preferred compounds for use as anesthetics are those in which R, R₁, and R₂ are hydrogen, in which R₃ and R₄ are ethyl groups and in which the

linkage in the structural formula is located, with respect to the phenylene group in the formula, at the para position. These preferred compounds, therefore, have the following fundamental structural formula:

where X is as above defined. It will be recognized that a portion of the formula, namely,

corresponds to the structure of procaine.

More specifically, the preferred compounds are those in which X is a saturated straight hydrocarbon chain containing from two to ten carbon atoms, preferably from two to six carbon atoms, namely, the ethylene, and the tri-, tetra-, penta-, and hexa-methylene compounds. These compounds are crystalline solids, whereas when X is a branched chain, the compounds are in general oily liquids. When X contains two carbon atoms (—CH₂—CH₂—), the compound has the following fundamental structural formula:

and may be designated the diethylaminoethyl ester of N,N' di (p-carboxy phenyl) ethylene diurethan, and the other preferred compounds may be similarly designated by the substitution of the appropriate designation of the saturated straight hydrocarbon chain for "ethylene" in the name of the compound.

As is well-known, amines generally, including procaine and modified or substituted procaines,

are formed into salts by addition of an acid to nitrogen in the molecule. These procaine salts, as well as the bases, are employed as anesthetics. Hence, the various compounds within the scope of this invention may be prepared and used either as the base or the salt. In the molecule of the compounds of the present invention, there are two basic nitrogens (the nitrogens to which the alkyl groups (R₃ and R₄) are attached) to which acid may be added to form a salt. Thus, for example, the structural formula for the hydrochloride of the compounds of the present invention may be written as follows:

In view of the fact that the salts differ only from the bases in the addition of the acid to the nitrogen atoms referred to, and are characterized by the same structural formula, the salts, as well as the bases, are included within the scope of this application and of the claims wherever reference is made to a compound comprising a stated structural formula.

The acid forming the salt may be any inorganic or organic acid desired, for example, hydrochloric, hydrobromic, hydroiodic, nitric, sulphuric, phosphoric, and the like; acetic and other acids of this series (for instance, propionic, caproic, stearic, and the like), crotonic, oleic, oxalic, citric, tartaric, lactic, benzoic, naphthoic, picric, salicylic, dilituric, and the like. It will be understood that with certain acids, the salt, while existing in solution and being usable as such may present difficulty in its isolation in solid form.

The compounds of the invention are readily prepared by condensing two mols of the appropriate aromatic amino base or a salt thereof, both of which are included within the term "aromatic amino compound," for instance, procaine or procaine hydrochloride, with one mol of the appropriate dichlorocarbonate or dibromocarbonate. The fundamental structural formula of the aromatic amino compound is represented by:

and the formula for the dihalocarbonate may be represented by:

where the various R's and other relationships and X are as heretofore defined in connection with the fundamental structural formula of the compounds of the invention and where Y is selected from the group consisting of chlorine or bromine.

The desired dichlorocarbonate or dibromocarbonate may be readily prepared by reacting, by known procedures, the appropriate dihydroxy compound (glycol), of which —X— in the above formula is the residue, with carbonyl chloride (phosgene) or carbonyl bromide. Generally, the required amount of the glycol is added slowly to the liquid carbonyl halide cooled in an ice bath. After the reaction is complete, the excess carbonyl halide is allowed to evaporate and the residue is advantageously warmed to remove traces of the carbonyl halide and the corresponding hydrogen halide. Alternatively, the carbonyl halide may be passed as a gaseous stream into the glycol maintained in an ice bath and after the reaction, the excess carbonyl halide

and the hydrogen chloride or bromide may be removed under reduced pressure.

In view of the fact that in preparing the compounds the use of a dichlorocarbonate is preferred, the invention will be described using such compound as the reactant but it is to be understood that if desired the dibromocarbonate may be used. The condensation of the dichlorocarbonate with the aromatic amino compound presents no problem because they are readily reactive and can be reacted directly, if desired. For manipulative reasons, however, it is desirable to conduct the reaction in the presence of a solvent such as water, acetone, alcohol, or mixtures thereof. Conventional chemical apparatus can be employed and it is usually desirable to add the aromatic amino compound, dissolved in a suitable solvent, into the reactor and to add the dichlorocarbonate dissolved in a suitable solvent from a dropping device. After the chemical reaction has subsided, the N,N'-substituted diurethan may be conveniently separated from the reaction mixture by removal of part or all of the solvent used during the reaction and filtration of the product if it is a solid. The diurethans which are liquids may be removed conveniently by extraction with a suitable solvent such as n-butanol or chloroform.

When the reaction is conducted in the absence of a basic material, the dihydrochloride salt of the compound is formed and the salt may then be treated with a basic material which will convert the salt into the base, that is, a basic material which is stronger than the N,N'-substituted diurethan formed. In the event it is desired to form the base directly, the condensation is conducted in the presence of a relatively strong base, examples of which are sodium hydroxide, potassium hydroxide, lithium hydroxide, calcium hydroxide, triethylamine, N-methyl piperidine, N-methyl morpholine, and any other basic material which will not enter into the reaction and which has a base strength greater than the base strength of the N,N'-substituted diurethan formed, thus reacting with the hydrogen chloride. If such a basic material is employed, it may be added to the reactants in any desired manner, for example, it may be added gradually to the reaction mixture by means of a dropping device, in which event, it is desirable to add the dichlorocarbonate at a rate so that there is present in the reaction mixture a slight excess of the dichlorocarbonate over the basic material at all times.

The reaction may be illustrated by the following equations, in which ethylene dichlorocarbonate is reacted with procaine, it being understood that the hydrochloride may be used in place of the free base, if desired:

(a) In the presence of a strong base:

(b) In the absence of a strong base:

The free base of the compound, either as obtained directly from the reaction or from the dihydrochloride, can be converted into any desired salt by reacting the base with the appropriate acid by conventional procedures, for example, by simply mixing the base and the acid in a solvent, if desired.

The following examples serve to illustrate further the present invention:

10

Example I

A solution of 5.45 g. (0.02 mol) of procaine hydrochloride, in 20 ml. of water, is warmed to 40°, and 1.87 g. (0.01 mol) of ethylene dichlorocarbonate, in 10 ml. of acetone, is added slowly. When the addition is about one-half complete, the first drop of a 7 ml. quantity of triethylamine is added. The addition of both reagents is controlled so that some free dichlorocarbonate is present at all times in the reaction mixture. After the addition of the triethylamine is completed, the mixture is warmed, with stirring, until the acetone is removed. The mixture is allowed to cool slowly and is then cooled to 5° and filtered to give 5.52 g. (94%) of a white product; M. P., 120–130°. This material is crystallized from a mixture of ethyl acetate and petroleum ether (B. P. 60–70°) to yield 4.91 g. (85%) of the N,N'-disubstituted diurethan which melts at 140–141°.

The compound is analyzed and is found to contain 61.18% C and 7.25% H. The formula for the compound is:

Following the same general procedure, the corresponding dimethylamino-, dipropylamino-, and dibutylamino derivatives may be prepared.

40

Example II

A solution of 33.4 g. (0.122 mol) of procaine hydrochloride, in 200 ml. of acetone and 25 ml. of water, is stirred while 14.0 g. (0.061 mol) of pentamethylene dichlorocarbonate is added dropwise. The solution turns cloudy rapidly and crystallization is complete within ten minutes after all of the dichlorocarbonate is introduced. The reaction mixture is cooled, filtered, and sucked as dry as possible. The white mass is dried in a vacuum oven at 65°/20 mm. to give 42.5 g. (99%) of product. After crystallization from a mixture of alcohol and n-hexane, the N,N' - disubstituted diurethan dihydrochloride melts at 176–177°.

The compound is analyzed and is found to contain 56.68% C and 7.30% H. The formula for the compound is:

Following the same general procedure, the salts of the corresponding dimethylamino- and dipropylamino derivatives may be prepared.

65

Example III

Using the procedure of Example I, except that trimethylene dichlorocarbonate is employed as the reactant, an N,N'-disubstituted diurethan is obtained of the structural formula:

The compound has a melting point of 116-117° C., and, upon analysis, 61.70% C and 7.14% H.

The compound is insoluble in water. However, upon the addition of acetic acid, the compound readily dissolves through formation of the acetic acid salt.

Example IV

Using the procedure of Example I, except that tetramethylene dichlorocarbonate is used as the reactant and acetone is used as the solvent for crystallization, an N,N'-disubstituted diurethan is obtained having the structural formula:

The compound has a melting point of 187-188° C., and, upon analysis, 62.50% C and 7.51% H.

Example V

Using the procedure of Example I, except that pentamethylene dichlorocarbonate is employed as the reactant, an N,N'-disubstituted diurethan is obtained having the structural formula:

The compound has a melting point of 156-157° C., and, upon analysis, 63.10% C and 7.83% H.

Example VI

Using the procedure of Example I, except that hexamethylene dichlorocarbonate is used as the reactant and alcohol is used as the solvent for crystallization, an N,N'-disubstituted diurethan is obtained having the structural formula:

The compound has a melting point of 190-191° C., and, upon analysis, 63.33% C and 7.74% H.

Example VII

Using the procedure of Example I, except that decamethylene dichlorocarbonate is used as the reactant and ethyl acetate is used as the solvent for crystallization, an N,N'-disubstituted diurethan is obtained having the structural formula:

The compound has a melting point of 160-161° C., and, upon analysis, 65.35% C and 8.50% H.

Example VIII

Using the procedure of Example I, except that bis 2,2'-oxydiethyl dichlorocarbonate is used as the reactant and a mixture of ether and petroleum ether (B.P. 60-70° C.) is used as the solvent for crystallization, an N,N'-disubstituted di-

urethan is obtained having the structural formula:

The compound has a melting point of 122-123° C., and, upon analysis, 60.65% C and 7.11% H.

Example IX

Using the procedure of Example II, except that ethylene dichlorocarbonate is used as the reactant, an N,N'-disubstituted diurethan dihydrochloride is obtained having the structural formula:

The compound has a melting point of 199-200° C., and, upon analysis, 54.93% C and 7.01% H.

Example X

Using the procedure of Example II, except that trimethylene dichlorocarbonate is used as the reactant and a mixture of alcohol and acetone is used as the solvent for crystallization, an N,N'-disubstituted diurethan dihydrochloride is obtained having the structural formula:

The compound has a melting point of 170-171° C., and, upon analysis, 55.05% C and 7.17% H.

Example XI

Using the procedure of Example II, except that tetramethylene dichlorocarbonate is used as the reactant and a mixture of alcohol and acetone is used as the solvent for crystallization, an N,N'-disubstituted diurethan dihydrochloride is obtained having the structural formula:

The compound has a melting point of 205-206° C., and, upon analysis, 56.00% C and 7.21% H.

Example XII

Using the procedure of Example II, except that 2-butyne-1,4-diol dichlorocarbonate is used as the reactant and a mixture of alcohol and ether is used as the solvent for crystallization, an N,N'-disubstituted diurethan dihydrochloride is obtained having the structural formula:

The compound has a melting point of 181-183° C., and, upon analysis, 56.35% C and 6.36% H.

Example XIII

Using the procedure of Example II, except that bis 2,2'-oxydiethyl dichlorocarbonate is used as the reactant and a mixture of methanol and ethyl acetate is used as the solvent for crystallization, an N,N'-disubstituted diurethan dihydrochloride is obtained having the structural formula:

The compound has a melting point of 191-192° C., and, upon analysis, 54.36% C and 7.18% H.

Example XIV

Using the procedure of Example II, except that decamethylene dichlorocarbonate is used as

9

the reactant and water is used as the solvent for crystallization, an N,N'-disubstituted diurethan dihydrochloride is obtained having the structural formula:

The compound has a melting point of 201-203° C., and, upon analysis, 59.23% C and 8.11% H.

Example XV

Using the procedure of Example II, except that 1,4 cyclohexylene dichlorocarbonate is used as the reactant and a mixture of methanol and acetone is used as the solvent for crystallization, an N,N'-disubstituted diurethan dihydrochloride is obtained having the structural formula:

The compound has a melting point of 213-214° C., and, upon analysis, 57.01% C and 6.77% H.

Example XVI

Using the procedure of Example II, except that p-phenylene dichlorocarbonate is used as the reactant and a mixture of alcohol and ether is used as the solvent for crystallization, an N,N'-disubstituted diurethan dihydrochloride is obtained having the structural formula:

The compound has a melting point of 164-166° C., and, upon analysis, 57.60% C and 6.21% H.

Example XVII

Following the procedure of Example I, except that propylene dichlorocarbonate is used as the reactant, an oily material is obtained. After

extraction with a mixture of n-butanol and chloroform and removal of the solvent, the base is converted to the dioxalate salt which is crystallized from a mixture of methanol and ether. The salt has the structural formula:

The compound has a melting point of 112-114° C., and, upon analysis, 53.54% C and 6.50% H.

Example XVIII

Following the procedure of Example XVII, except that 2-methyl trimethylene dichlorocarbonate is used as the reactant and a mixture of alcohol and ether is used as the solvent for crystallization of the salt, an N,N'-disubstituted di-

urethan dioxalate is obtained having the structural formula:

The compound has a melting point of 115-117°

10 C., and, after analysis, 54.69% C and 6.46% H.

Following an analogous procedure, the disalicylic and didilituric acid salts of the corresponding tetramethylene derivative (i. e. tetramethylene instead of 2-methyl trimethylene in the above formula) are prepared. The disalicylate is a white powder having a melting point of 140.5-141.5° C., and the didiliturate has a melting point of 235-236° C.

Example XIX

Following the procedure of Example XVII, except that 1-methyl trimethylene dichlorocarbonate is used as the reactant, an N,N'-disubstituted diurethan dioxalate is obtained having the structural formula:

The compound has a melting point of 162-164° C., and, upon analysis, 54.33% C and 6.30% H.

Example XX

Following the procedure of Example XVII, except that 3,3-dimethyl pentamethylene dichlorocarbonate is used as the reactant and alcohol is used as the solvent for crystallization of the salt, an N,N'-disubstituted diurethan dioxalate is obtained having the formula:

The compound has a melting point of 150-152° C., and, upon analysis, 55.86% C and 6.70% H.

Example XXI

Following the procedure of Example XVII, except that 2-methyl trimethylene dichlorocarbonate is used as the reactant and the dipicrate salt is formed, an N,N'-disubstituted diurethan is obtained having the structural formula:

70 The compound has a melting point of 130-131° C., and, upon analysis, 49.00% C and 4.79% H.

Example XXII

Following the procedure of Example XVII, except that 1-methyl trimethylene dichlorocarbonate is used as the reactant and the dipicrate

salt is formed, an N,N'-disubstituted diurethan dipicrate is obtained having the structural formula:

The compound has a melting point of 144-145° 10 C., and, upon analysis, 49.51% C and 5.19% H.

Example XXIII

A solution of 5 ml. of water and 10 ml. of acetone, containing 1.28 g. (0.004 mol) of 2-diethylaminoethyl o-methoxy-p-aminobenzoate is prepared. To this solution is added 0.240 g. (0.002 mol) of tetramethylene dichlorocarbonate. The mixture is allowed to stand for three days and 0.21 g. (0.002 mol) of triethylamine is then added. The mixture is warmed on a steam bath until all of the acetone is removed, after which 10 ml. of water is added. This mixture is then extracted with chloroform, the organic layer dried and the solvent removed. The residual oil is dissolved in ether and the solution is saturated with dry hydrogen chloride. The white solid which is obtained in good yield is collected and crystallized from a mixture of methanol, ethyl acetate and ether.

The product has the structural formula:

The compound has a melting point of 148-150° C., and, upon analysis, 54.69% C and 7.28% H.

Compounds formed by reaction of the dichlorocarbonates with 2-diethylaminoethyl o-isopropyl-p-aminobenzoate; 2-diethylaminoethyl o-butoxy-p-aminobenzoate, and their salts, are also prepared in the same general manner.

Example XXIV

To 13 g. (0.04 mol) of crude 2-diethylamino-1-methylethyl p-aminobenzoate in alcohol is added 4.7 g. (0.02 mol) of tetramethylene dichlorocarbonate. The mixture is heated to remove the excess alcohol and upon cooling 6 g. of a crystalline product is obtained. After crystallization 50 from alcohol, the diurethan dihydrochloride:

is obtained. The compound has a melting point of 176-178° C., and, upon analysis, 57.29% C and 7.02% H.

Compounds formed by reaction of the dichlorocarbonates with 2-diethylamino-2-methylethyl p-aminobenzoate and 2-diethylamino-3-methylbutyl p-aminobenzoate, and their salts, are also prepared in the same general way.

Considerable modification is possible in the selection of the various constituents and combinations of constituents and in the particular salt formed, where desired, as well as in the par-

ticular techniques employed in preparing the compounds without departing from the scope of the invention.

I claim:

1. N,N' - disubstituted diurethans comprising the structure:

where X is selected from the group consisting of a saturated straight hydrocarbon chain containing from two to ten carbon atoms, a saturated branched hydrocarbon chain containing from three to ten carbon atoms, an unsaturated hydrocarbon chain containing from four to ten carbon atoms, a phenylene group, a cyclohexylene group, and an ether linkage —R'—O—R'— where R' is selected from the group consisting of ethylene, trimethylene and propylene.

2. N,N' - disubstituted diurethans comprising the structure:

where n is a number from two to ten.

3. N,N' - disubstituted diurethans comprising the structure:

where n is a number from two to six.

4. An N,N'-disubstituted diurethan comprising the structure:

5. An N,N'-disubstituted diurethan comprising the structure:

6. An N,N'-disubstituted diurethan comprising the structure:

7. An N,N'-disubstituted diurethan comprising the structure:

8. An N,N'-disubstituted diurethan comprising the structure:
